UNITED STATES PATENT OFFICE

158,484

CALENDAR HOLDER OR THE LIKE

Mario J. Manetti, Chicago, Ill., assignor to Plastic Novelty Co., Chicago, Ill., a corporation of Illinois

Application October 28, 1949, Serial No. 5,744

Term of patent 7 years

(Cl. D74—5)

To all whom it may concern:

Be it known that I, Mario J. Manetti, a citizen of the United States, residing at Chicago, in the county of Cook and State of Illinois, have invented a new, original, and ornamental Design for a Calendar Holder or the like, of which the following is a specification, reference being had to the accompanying drawing, forming part thereof.

In the drawing:

The dominant features of my design reside in those portions shown in full lines.

I claim:

The ornamental design for a calendar holder or the like, as shown and described.

MARIO J. MANETTI.
